HAIR CLASP

Albin J. Spokus, Seattle, Wash.

Application September 2, 1947, Serial No. 771,689

3 Claims. (Cl. 132—48)

1

This invention relates to improvements in hair clasps and, more particularly, to devices for holding ornaments in the hair in a quickly attachable and detachable manner, yet with firmness.

It is a prime object of this invention to provide a holder for hair ornaments which can quickly and easily be engaged with an ornament, without requiring skill on the part of the user.

It is also an object of this invention to provide a hair-clasping holder for ornaments which is not easily dislodged in use and which holds an ornament against non-intentional dislodgement.

Another object of the invention is to provide, in a hair clasp of the type described, a clasping element that can simply and quickly be brought into clasping position without skill or difficulty on the part of the user.

Yet another object resides in the provision in a hair clasp of gripping elements that will receive a variety of sizes and shapes of ornaments, without permitting accidental dislodgement even though violently handled or treated.

The foregoing objects and others ancillary thereto I prefer to accomplish as follows:

According to a preferred form of my invention, I mount upon a hair clasp a clamping or gripping element to secure ornaments to the clasp. Specifically, the hair clasp comprises a U-shaped element, formed of resilient and springy material, such as spring steel or the like, so shaped and arranged that the legs are biased together to straddle and clasp a lock of hair. One of the legs is longer than the other and has an intermediate series of dentations of various sizes along its length. The dentations are arranged so that the grooves are lateral of the leg with the obverse portion outward, and the reverse portion overlying the other leg, whereby a lock of hair is securely gripped. A spring blade overlies the obverse of said dentations by having one end slidably encircling the dentate leg between the grooves and the bend of the U-shape. The other end of the blade also has a loop that will slip over the end of the dentate blade and hold it securely thereto.

The novel features that I consider characteristic of my invention are set forth with particularity in the appended claims. The invention itself, however, both as to its organization and its method of operation, together with additional objects and advantages thereof, will best be understood from the following description of a spe-

2

cific embodiment when read in connection with the accompanying drawing, in which:

Fig. 1 is a perspective view of my hair clasp in the closed position;

Fig. 2 is a similar view of the clasp in the open position;

Fig. 3 is an enlarged cross-sectional view taken on line 3—3 of Figs. 1 and 2; and

Fig. 4 is a fragmentary view showing the clasp as gripping the stem of a flower.

A hair clasp, to meet the objects of this invention, must be simple to construct and use; it must be capable of receiving and securely gripping an ornament; and it must keep the ornament placed in the hair as desired by the user. Accordingly, a preferred embodiment of the invention, referring to Figs. 1 and 2 of the drawing, is constituted by a U-shaped hair clasp that carries a clamping member with respect to

certain ornament-receiving elements. The hair clasp includes the spring legs 10 and 12 which are integral with each other, being joined by the U-bend portion 14. Preferably, I use spring bar material, such as spring steel or the like, bent and shaped as shown, and biased together to a gripping position.

Leg 12 is deformed in a zig-zag manner to form dentations that provide grooves 16, 18 and 20, and the teeth 17, 19 and 21 that are directed toward leg 10. When the clasp is astraddle a lock of hair, the teeth 17, 19 and 21 bite into the lock and grip it securely, due to the biasing of the legs together and the action of the spring material from which they are formed.

Leg 10 has its end 11 curved to facilitate spreading of the legs, as a user will normally insert a thumb or finger nail between the legs and twist them apart.

A spring blade 24 overlies the grooves 16, 18 and 20, and is formed to curve, in the open position, away from leg 12, so that an ornament may be inserted in one of the grooves. Blade 24 is slidably secured to leg 12 between bend 14 and groove 16 by bent-over ears 26 that form a sliding couple. The other end of the spring blade also has ears 26 which form a loop to slip over the free end 13 of blade 12, when the blade is distorted from the curved position into alignment, as shown in Fig. 1. When so closed, the blades will grip

a flower stem S, or other ornament, as suggested in Fig. 4. If the thing to be gripped is larger, the groove 16 will be used and similarly groove 20 will receive smaller objects. A bow may be formed of ribbon by knotting, and then blade 24 is passed through the knot or around it and

closed toward blade 12, and is there secured by having the loop at the free end slipped over end 13 of blade 12. It is desirable that the grooves and teeth of blade 12 lie generally to one side of the plane of said blade, so that blade 24 will lie outside the grooves and the teeth will protrude to enter and form strands in a lock of hair.

It has been found that this clasp will firmly hold a heavy flower in relatively light, thin hair, without displacement, even though the wearer may be actively dancing or swinging her head. Yet the device is easily removed from the hair and the ornament from the gripping jaws without difficulty.

While I have shown and described particular embodiments of my invention, it will occur to those skilled in the art that various changes and modifications may be made without departing from the invention, and I therefore aim in the appended claims to cover all such changes and modifications as fall within the true spirit and scope of my invention.

Having thus described my invention, I claim:

1. A device for holding ornaments in the hair, comprising: a springy U-shaped element to straddle a lock of hair and having its legs biased together, one of said legs being longer than the other and having an intermediate series of vari-sized dentations the grooves of which lie non-perpendicular and lateral to the axis of the shorter leg, a spring blade overlying said dentations and slidably secured to said longer leg between said dentations and the bend of said U-shaped element, and means for securing said spring blade to the end of said longer leg to grip an ornament between said leg and blade in one of said dentations.

2. A device for holding ornaments in the hair, comprising: a springy U-shaped element to straddle a lock of hair and having its legs biased together, one of said legs being longer than the 40

other and having an intermediate series of vari-sized dentations the grooves of which lie non-perpendicular and lateral to the axis of the shorter leg, a spring blade overlying said dentations and slidably secured to said longer leg on one side of said dentations, and means for securing the unsecured end of said spring blade to said longer leg on the other side of said dentations to grip an ornament between said leg and blade in one of said dentations.

3. A device for holding ornaments in the hair, comprising: a springy U-shaped element to straddle a lock of hair and having its legs biased together, one of said legs being longer than the other and having an intermediate series of vari-sized dentations the grooves of which lie non-perpendicular and lateral to the axis of the shorter leg, a spring blade overlying said dentations and having an encircling loop slidably engaged about said longer leg between said dentations and the bend of said U-shaped element, and a second loop carried by the other end of said spring blade to engage the end of said longer leg to grip an ornament between said leg and blade in one of said dentations.
